FIREPLACE

Dannie O. Malafouris, 7945 NE. Alberta,
Portland, Oreg. 97218

Filed Dec. 4, 1968, Ser. No. 14,786

Term of patent 14 years

Int. Cl. D23—03

U.S. Cl. D23—97

Fig. 1.

Fig. 2.

FIG. 1 is a view in front elevation and
FIG. 2 is a view in side elevation of the fireplace.
FIG. 3 is a fragmentary sectional view taken on line
3—3 of FIG. 1.

The design of the side of the fireplace not shown is the same as the design of the side shown, and the bottom and back of the fireplace are plain.

The dominant features of my design reside in the full line showing.

I claim:

The ornamental design for a fireplace, as shown and described.
